UNITED STATES PATENT OFFICE.

CARL H. KIRKENDALL, OF NEW YORK, N. Y.

GREASE-GUN.

1,180,046.

Specification of Letters Patent. Patented Apr. 18, 1916.

Application filed June 8, 1915. Serial No. 32,867.

To all whom it may concern:

Be it known that I, CARL H. KIRKENDALL, a citizen of the United States and a resident of the city of New York, borough of 5 Manhattan, in the county and State of New York, have invented a new and Improved Grease-Gun, of which the following is a full, clear, and exact description.

My invention relates to grease guns, and 10 an object of the invention is to provide, a simple, strong, inexpensive, and efficient grease gun the plunger of which can be driven totally into the barrel without ejecting the contents thereof, if so desired.

15 A further object of the invention is to provide a grease gun the length of which can always be maintained at its minimum, whether the gun is full or not.

With the above and other objects in view, 20 the nature of which will more fully appear as the description proceeds, the invention consists in the novel construction, combination and arrangement of parts as herein fully described, illustrated and claimed.

25 In the accompanying drawings, forming part of the application, similar characters of reference indicate corresponding parts in all the views.

Figure 1 is an elevation partly in section showing the detail of construction of 30 my grease gun; Fig. 2 is a cross section on line 2-2, Fig. 1; and Fig. 3 is a cross section on line 3-3, Fig. 1.

Referring to the drawings, 4 represents 35 the barrel of the gun, which has preferably one end 5 thereof reduced and wherat a nozzle 6 is provided through which the contents may be received and ejected. Fitting snugly in the gun are plunger sections 40 7 and 8. The plunger section 7 engages a key 9 secured to the lateral surface of the gun which prevents the turning of the section 7 within the gun, although it permits the sliding thereof. A plunger rod 10 pro- 45 jects through the plunger sections 7 and 8. Said rod is free to turn in the section 7, while the section 8 is keyed to the rod and constrained to turn therewith when the rod 10 is turned within the section 7. The lon- 50 gitudinal displacement of the rod relative to the section 7 is prevented by the section 8 and nuts 11 secured to the projecting end of the rod adjacent the plunger section 7. Plunger sections 7 and 8 have cut-outs 55 or openings 12 which are preferably sec- torial in shape and wherethrough the end

of the barrel on the side of the plunger section 8 can be brought into communication with the end of the barrel on the side of the plunger section 7. 60

To control the relative position of the plunger sections 7 and 8, the turning move- 65 ment of section 8 relative to section 7 is limited. This limitation can be obtained by any suitable means, but preferably the sec- torial cut-out 12 of the plunger section 8 is made to engage the key 9, whereby, in turning the rod 10 to the right the open- 70 ings 12 of the two sections will be brought in register; and by turning the rod to the left, the openings of the two sections will be closed by the solid parts of the two sec- 75 tions. Therefore, when the gun is closed by the cup 13, the operator will know at once whether the openings 12 of the two plunger sections are in register or not by trying to turn the rod to the right. If it does not turn, the two openings of the sec- 80 tions are in register.

If the operator wishes to sever communica- 85 tion between the two ends of the barrel, he tries to turn the rod to the left, and if the rod turns he brings it to the position indicated in Fig. 2, that is, until the rod will not turn farther, whereby by pulling the 90 rod out of the barrel a substance can be introduced into the barrel, and by forcing the rod into the barrel the substance may be ejected. If some of the substance remains within the barrel it is not necessary to eject 95 it to shorten the gun, it is only necessary to bring the openings 12 of the plunger sec- 100 tions 7 and 8 in register by turning the rod as previously described, and then by forcing the rod into the barrel, the contents within the barrel at the nozzle end thereof will be transferred to the other end of the barrel 105 through the openings in the plunger sec- tions. When it is desired to use the contents which have been transferred to the cap end 110 of the barrel, the rod 10 is pulled, while the openings 12 of the plunger sections 7 and 8 are in register, thus causing the contents to flow from the cap end toward the nozzle end through the openings 12 of the plunger sec- 115 tions. By severing the register of the open- ings in the plunger sections 7 and 8, and by forcing the rod into the barrel, the contents thereof may be ejected.

While I have described the principle of 110 operation, together with the device which I now consider to be the best embodiment

thereof, I desire to have it understood that the device shown is merely illustrative and that such changes may be made as are within the scope of the appended claims.

5 I claim:

1. In a grease gun of the class described, a barrel having a nozzle at one end, a plunger rod projecting through the other end, plunger sections associated with said rod and barrel so that one of the sections can be turned relative to the other within the barrel, and means engaging the other section whereby the same is prevented from turning but is free to slide in the barrel, the 10 said means limiting the turning movement of the first section, said sections having openings adapted to be brought in register by the turning movement of the section whereby the two portions of the barrel to each side of the plunger can be brought into communication.
- 15 2. In a grease gun of the class described, a barrel having a nozzle at one end, a key within on the lateral surface of the barrel

extending substantially through the entire 25 length thereof, a plunger section engaging the key so that it is free to slide within the barrel but prevented from turning therein, a piston rod projecting through the other end of the barrel and mounted to turn in the 30 plunger section but prevented from longitudinal movement relative thereto, and a second plunger section adjacent the first constrained to turn when the rod is turned, said sections having sectorial openings adapted 35 to register when the rod is turned, said second plunger section having means engaging the key whereby the turning movement of the same is limited within the barrel and whereby the proper register of the openings 40 in the plunger sections is obtained.

In testimony whereof I have signed my name to this specification in the presence of two subscribing witnesses.

CARL H. KIRKENDALL.
